UNITED STATES PATENT OFFICE.

MICHAEL J. DINNEEN, OF LOWELL, MASSACHUSETTS.

CIRCULAR-KNITTING MACHINE.

SPECIFICATION forming part of Letters Patent No. 415,834, dated November 26, 1889.

Application filed June 8, 1889. Serial No. 313,551. (No model.)

To all whom it may concern:

Be it known that I, MICHAEL J. DINNEEN, a citizen of the United States, residing at Lowell, in the county of Middlesex and Commonwealth of Massachusetts, have invented a certain new and useful Improvement in Circular-Knitting Machines, of which the following is a specification.

My invention relates to circular-knitting machines; and it consists in the devices and combinations hereinafter described and claimed, which enable a circular-spring-needle knitting-machine to knit one or more courses of a yarn of one color and then one or more courses of a yarn of a different color, and to change automatically from one color to another by first introducing one yarn and immediately thereafter severing the yarn previously being knitted.

In the accompanying drawings, Figure 1 is an isometric view of so much of a circular spring-needle knitting-machine as is necessary for an understanding of my invention with my improvement attached thereto, showing a part of a needle-cylinder and its needles and the loop-wheel and its stand; Fig. 2, a broken plan of the parts of my improvement, partly in section, showing the yarn-guide levers, the upper fluted roll, the table on which said levers are supported, the pattern-tape, the pattern-wheel, its ratchet, the pawl-rod, its pawl, spring, and anti-friction pulley, the pattern-tape, the carrier-wheel, and the bracket which supports the same and on which the same is adjustable; Fig. 3, a section on the line 3 3 in Fig. 2 of the pattern-wheel and a part of the table which supports the yarn-guide levers, showing said yarn-guide levers, the pattern-tape, and a part of said table in side elevation, and showing the fluted rolls in end elevation and one of the springs, partly in dotted lines, in side elevation; Fig. 4, a section on the line 4 4 in Fig. 2; Fig. 5, a section of a part of the loop-wheel and of a part of the cylinder parallel with one of the leaves of said loop-wheel, showing also a yarn being operated upon by the machine and two other yarns in readiness to be introduced into the machine; Fig. 6, an isometric view of one of the leaves of the loop-wheel provided with a cutting-edge; Figs. 7 and 8, respectively, a side elevation and an

outer edge elevation of one of said leaves; Fig. 9, a transverse section on the line 9 9 in Fig. 7.

The needle-cylinder A, needles a, loop-wheel stand b, and loop-wheel B, except that the leaves of the loop-wheel are sharpened into cutting-edges, as hereinafter described, are of the usual construction and operation and are used with other parts commonly used in circular spring-needle knitting-machines, including a sinker-wheel or divider-wheel, landing-wheel, and presser-wheel, and a push-back C. (Shown in Fig. 1.)

The yarns y' y² y³, Fig. 1, of which there are two or more, three being shown, each run through a separate yarn guide or lever G' G² G³ from bobbins, (not shown,) each yarn-guide being provided with a yarn-eye g' g² g³ to admit a yarn, and then under the inner end of said yarn-guide or end nearest the needle-cylinder A; then through a vertical comb H, having vertical slits h' h² h³, each adapted to receive a yarn and keep it out of contact with the other yarns and to hold each yarn under its own yarn-guide lever, in order that it may be held thereby, as hereinafter described; then between fluted rolls I I', arranged between said comb H and said needle-cylinder parallel with said comb, and from the fluted rolls over the yarn-table J to the loop-wheel or stitch-wheel B, which operates upon said yarns one at a time in the usual manner.

The yarn-guide levers G' G² G³ are independently pivoted on a horizontal rod K, supported in a frame L, which is also pivoted at l near the outer ends of said yarn-guide levers to brackets m m, secured to a table M. The table M also supports the comb H, the bearings of the lower fluted roll I', and the yarn-table J, and is itself supported upon the upper part of a stand N, similar to the stand which supports the loop-wheel in the respect that it is formed in two parts, the upper part n of which is hollow and vertically adjustable on the lower part, said lower part being a vertical rod rigidly secured in the bed of the machine to enable the parts supported thereby to be raised to the proper height with reference to the loop-wheel, said upper part n being held at the proper height by means of a set-screw n², which turns radially in said

55

upper part and thrusts against said rod. The object of pivoting the frame L is to enable said frame, and with it the yarn-guide levers to be raised to pass the yarns through the 5 yarn-eyes $g' g^2 g^3$ and through the comb. After the yarns have been arranged in the yarn-eyes and comb the frame is turned down on the table M and there held by turning the cap-screw O until its head o extends over the 10 top of said frame, said screw turning in a vertical threaded hole in the table M and having one side of its head cut away at o' to allow the frame to be raised when the last-named side is turned toward the frame.

15 The under side of the inner end of each yarn-guide lever is provided with a transverse rib g^4 , between which and the table M or a plate m' , supported on said table M, the yarn belonging to said lever is clamped when 20 the outer end of said lever is raised, as herein-after described. When any yarn is thus clamped, it will be broken or cut by a leaf b' of the loop-wheel B where the yarn enters the needles.

25 The loop-wheel B, as above stated, performs the ordinary functions of a loop-wheel or stitch-wheel—that is, its leaves push the yarn between the needles and form loops in said yarn—and at the same time its nibs b^2 or the 30 projecting lower ends of its leaves below the notches b^3 of said leaves carry the yarn up under the beards a' of the needles a ; but to insure a more perfect operation of the severing devices and to avoid straining and bending 35 the needles the notches b^3 are on their upper sides sharpened into knives b^4 , and the effect of clamping the yarn by the yarn-guide levers is to strain the yarn and cause it to rise on the leaves of the loop-wheel onto 40 said knives b^4 , by which knives the yarn is immediately cut. The severed end of the yarn then lies upon the yarn-table J in close proximity to the loop-wheel and needles, in readiness to be reintroduced into the fabric.

45 The yarn-table J is of a suitable shape to fill the space between the loop-wheel, the needles, and the table M, and is provided with a slotted ear j, through which passes a screw j' into said table M, adjustably securing the 50 yarn-table J to said table M. The side j^3 of the yarn-table J is curved to conform to the curvature of the row of needles, and is arranged as near as possible to said needles without being in contact with them, and 55 keeps the loose yarns and the welt or portion of previously-knit fabric placed on the needles and extending outside of the circle of needles down from being caught between the loop-wheel and the needles, and the upper 60 corner of said yarn-table is fitted as closely as possible without being in contact therewith to the loop-wheel and the needles, so that the yarn cannot fall below the loop-wheel and fail to be caught by said wheel and the needles.

65 All the yarns pass between the fluted rolls I I', the flutes i' of which engage one another.

The axes of said fluted rolls are horizontal and the journals of the lower roll I turn in suitable boxes i^3 in the table M, while the journals of the upper roll I' turn in journal-boxes i^4 in the frame L, above described. The journal-boxes i^4 of the upper fluted roll I are open at the top and are filled with blocks i^6 , Fig. 3, which bear upon the journals of said upper fluted roll, being held in contact therewith by springs i^7 , which are represented as being leaf-springs secured by screws i^8 to the frame L, the free ends of said springs pressing upon the blocks i^6 and being preferably riveted to or otherwise secured to said block. Lifting the frame L not only raises the yarn-guide levers, as above described, but also raises the upper fluted roll I and facilitates the placing of the yarn between the rolls. The fluted rolls are driven at a constant rate of speed when the machine is in operation by the friction of the yarn or yarns which, for the time being, are entering the machine, the broken yarn (having no tension placed upon it, the fluted rolls not bottoming in each other) merely standing still, bending, as shown in Fig. 10, to conform to the action of the rolls; but, when the broken yarn is unclamped the rolls will carry the free end of said broken yarn 95 far enough to allow it to be caught by the loop-wheel and knitted into the fabric. After both yarns have entered the fabric together for a few stitches, just enough to make sure that the new yarn will not slip away from 100 the loop-wheel and needles, the old yarn is clamped by its yarn-guide lever and cut or broken, as above described.

To the under side of the outer arm of each yarn-guide lever is secured an adjustable 105 spring-follower $g^5 g^6 g^7$ by means of a screw $g^9 g^{10} g^{11}$, which passes through an unthreaded hole in said yarn-guide lever and enters the inner end of the nearly horizontal part of said follower, and an adjusting-screw $g^{13} g^{14} g^{15}$ turns in each lever and thrusts down upon said follower between the attaching-screw $g^9 g^{10} g^{11}$ and the other end of said follower to vary the distance of the lower end of said follower from its lever, the elasticity of the 115 follower holding it constantly against the lower end of its adjusting-screw. The outer ends of the followers are bent downward to enter the pattern-grooves in the pattern-tape Q, herein-after described. Below the outer 120 ends of the yarn-guide levers turns the pattern-drum P, its axis being parallel with the fulcrum-rod K and its periphery being provided with as many annular grooves $p' p^2 p^3$ (see Fig. 1) as there are yarn-guide levers 125 which grooves are capable of receiving the outer lower ends of said followers when the inner ends of said levers are raised. A pattern-tape Q, preferably of sheet metal, runs on the drum P and on a carrier-wheel P', the office of said carrier-wheel being merely to support the tape and to furnish a means of keeping said tape taut, said carrier-wheel 130 turning on a stud p^{13} , provided with an en-

larged shoulder p^{14} and extending through a slot p^{15} in a bracket p^{16} , secured by a screw p^{17} to the same bench or stand which supports the knitting-machine proper. The 5 drum P and the carrier-wheel P' may be set farther apart by loosening the nut p^{18} , which turns on the threaded outer end of the stud p^{13} away from the bracket p^{16} , and then moving said shaft in the slot p^{15} away from said drum 10 P. The stud p , after being adjusted in such a position as to strain the tape Q, may be held in position by turning said nut p^{18} on said stud against said bracket. The drum P and carrier-wheel P' may be provided with flanges 15 p^{19} p^{20} to prevent the tape from moving laterally on said drum and carrier-wheel. The drum P is supported and turns in journal-boxes n^7 in the frame n^4 , said frame being supported on the stand N and vertically adjustable thereon, being held by a set-screw n^5 , which passes through a sleeve n^6 , secured to said frame n^4 , and thrusts against said stand N. The pattern-tape Q has a number of slots equal in number to the yarn-guide levers and 20 to the grooves in the drum P, said slots q' q^2 q^3 being arranged at the same intervals with said grooves and coming directly over said grooves. The lower end of each follower is beveled at g^{17} g^{18} g^{19} downward and inward 25 30 toward the needle-cylinder, and is provided just below the top of the bevel on one or both sides with shoulders or stops g^{21} g^{22} g^{23} , which rest on the tape Q when the lower ends of said followers are in the slots of said tape 35 and limit the upward movement of the inner ends of the yarn-guide levers. When the drum P is rotated in the direction of the arrow marked thereon, the pattern-tape is carried with it, and to prevent said tape from 40 slipping on said drum the drum is provided with a series of radially or nearly radially projecting pins p^{21} , arranged at equal intervals on said drum and entering holes q , arranged at corresponding equal intervals in 45 said tape near the sides thereof. When the radial pins p^{21} and the holes q are used, the flanges p^{19} are not absolutely essential.

Each yarn-guide lever releases its yarn when its follower enters a pattern-slot, the 50 front arm of said lever being raised by a leaf-spring g^8 , secured to the table M and pressing against the under side of said lever, and immediately afterward another lever is caused to clamp its yarn by the end of a pattern-slot 55 striking the beveled end of its follower.

The drum P is provided with an annular ratchet p^5 , engaged by a pawl r ; adjustably secured on the pawl-rod R, which slides in horizontal bearings n^2 n^3 , secured to the frame 60 n^4 , above named. The pawl r turns on a vertical stud r' on the inner end of a bolt n^2 , which passes through a longitudinal slot r^3 in the pawl-rod R and carries a nut r^4 on its outer end, which, being turned, draws a shoulder r^5 , with which said bolt is provided, against the inner side of said pawl-rod. By 65 this means the distance of the pawl from

the inner end of the pawl-rod may be varied, and the shoulder r^5 and nut r^4 act as stops to limit the motion of the pawl-rod toward the cylinder. The pawl is kept in engagement with the ratchet by the spring r^6 . The rod R is pressed toward the needle-cylinder by a spiral spring r^7 , which surrounds said rod R and is compressed between the inner bearing n^3 of said rod and the enlarged head r^8 of said rod. The inner end of the rod R supports an anti-friction roll r^9 , and the needle-cylinder A has secured to it a cam a^2 , which once in every revolution of said cylinder 75 strikes said roll and throws the pawl-rod outward and rotates the drum P an angular distance represented by one tooth of the ratchet p^5 and moves the pattern-tape Q an equal amount. In order that the drum may not be 80 thrown too far by the action of the pawl, the journal-boxes n^7 are open at the top and a plug of leather or similar material n^8 is inserted in the tops of said journal-boxes and pressed down upon the journals p^{22} of said 85 drum by means of clamp-bars p^{23} , arranged above said journal-boxes or journal-slots and drawn by screws p^{24} , passing through the ends of said bars on opposite sides of said journal-boxes into the top of the frame n^4 to create a 90 friction between said plugs and said journals and to stop the drum as soon as the outward movement of the pawl-rod R stops. 95

The cam a^2 has two cam-surfaces a^3 a^4 , one a^3 of which first rotates the drum far enough 100 to allow one of the yarn-guide levers to be operated to release its yarn, which immediately enters the machine, the inner side of the pawl-rod or its anti-friction roll then resting upon a surface a^5 of the cam, which rest 105 or surface a^5 is concentric with the cylinder A, the angular length of this surface determining the distance which the two yarns—the old and the newly-introduced—shall enter the machine together. When the newly-introduced yarn has entered the fabric sufficiently, the pawl-rod is thrown farther outward by the second cam-surface a^4 and rotates the pattern-drum sufficiently to cause 110 the old yarn to be clamped by its yarn-guide lever, the slots of the pattern-tape lapping past each other sufficiently for this purpose. 115

It will be understood that the width of the different stripes of the fabric depends on the length of the slots in the pattern-tape Q—that 120 is, that the number of courses of yarn of any color will be equal to the number of teeth of the ratchet p^5 , which represents the angular distance measured by the pattern-slot, which allows the yarn of that color to enter the machine, supposing the tape to be wound about 125 the drum P.

When it is desired to use the machine without the striping devices, the pawl-rod may be drawn outward until the hole p^{10} in the 130 pawl-rod is in line with the hole n^9 in the bearing n^2 and there held by inserting the pin p^{11} in both of said holes, which will hold the pawl-rod out of engagement with the

cam a' , and thus allow the yarn then running into the fabric to knit a solid color until such time as the pin p^{11} is withdrawn to allow the pawl-rod to be moved by the spring r^7 into the path of said cam. The pin p^{11} may be conveniently attached to the machine by a chain p^{12} , as shown in Fig. 1.

The rolls I I' , instead of being fluted, may be covered with leather or other similar material adapted to draw the yarns by friction, and may be connected by positive mechanism with a revolving part of the machine, but, if fluted, should be used with stops r^9 , which may be hooks arranged to project from the top of the frame L and to be turned over the spring r^7 to prevent the top roll from rising out of its journal-boxes and to be turned in the other direction when desired to remove the top roll.

20 The followers g^5 g^6 g^7 are each provided with an upward projection g^{12} , which enters a corresponding recess g^{13} (shown by dotted lines in Fig. 3) in the under side of its yarn-guide lever to prevent said follower turning on said lever and getting out of the plane of the corresponding pattern-slot.

Instead of the pattern-tape Q , a pattern-chain of any desired length and provided with projections to strike the beveled ends of the 30 followers may be carried by the drum.

The ribs g^4 of the yarn-guide levers may be covered with a suitable pad or may strike upon a pad of material best adapted to prevent the yarn from slipping when clamped.

35 The yarn-table J may be dispensed with and the yarn allowed to fall on the top of the plates a^6 , by which the needles are clamped to the cylinder, or the ends of the yarn may be held by the suction of the current of air 40 set in motion by the rapid revolution of the needle-cylinder at the proper place to be caught by the loop-wheel and the needles; but it is considered safer to support the severed ends of the yarn by said table J , which 45 insures the proper introduction of the yarns into the machine.

I claim as my invention—

1. The loop-wheel having leaves provided with nibs, said leaves having their edges above 50 said nibs sharpened to form knives, as and for the purpose specified.

2. The combination of the needle-cylinder and needles and the loop-wheel provided with leaves having cutting-edges, as and for the 55 purpose specified.

3. The combination of the needle-cylinder having needles, the loop-wheel, and the feed-rolls adapted to feed yarns placed between said rolls, as and for the purpose specified.

60 4. The combination of the needle-cylinder having needles, the loop-wheel, and the feed-rolls adapted to be rotated by a yarn drawn between the same and to feed other yarns placed between said rolls, as and for the purpose specified.

65 5. The combination of the needle-cylinder having needles, the loop-wheel, and the fluted

feed-rolls adapted to engage each other and to be rotated by a yarn drawn between said rolls and to feed other yarns placed between 70 said rolls, as and for the purpose specified.

6. The combination of the needle-cylinder having needles, the loop-wheel, and the feed-rolls arranged one above the other, the upper of said rolls having upwardly-yielding bearings, said rolls being adapted to be rotated by a yarn drawn between the same and to feed other yarns placed between said rolls, as and for the purpose specified.

7. The combination of the needle-cylinder 80 having needles, the loop-wheel, the feed-rolls adapted to be rotated by a yarn drawn between the same and to feed other yarns placed between said rolls, and the yarn-table arranged between said rolls, needles, and loop-wheel, as and for the purpose specified.

8. The combination of the needle-cylinder provided with needles, the loop-wheel, feed-rolls, a table, and yarn-guides pivoted thereon and adapted to clamp between their ends and 90 said table yarns, as and for the purpose specified.

9. The combination of the needle-cylinder provided with needles, the loop-wheel, feed-rolls, a table, yarn-guides pivoted thereon and 95 adapted to clamp between their ends and said table yarns, and having downwardly-projecting rear ends, the pattern-tape, the pattern-drum provided with a ratchet, a pawl-rod carrying a pawl, a spring forcing said pawl-rod toward said cylinder, and a cam secured on said cylinder and adapted to push said pawl-rod and turn said pattern-drum at every revolution of said cylinder, as and for the purpose specified.

10. The combination of the needle-cylinder provided with needles, the loop-wheel, feed-rolls, a table, yarn-guides supported thereon and adapted to clamp between their inner 110 ends and said table yarns, and having adjustable followers provided with downwardly-projecting rear ends, a pattern-tape having slots to receive said downwardly-projecting rear ends, the pattern-drum and the carrier-roll, said pattern-drum having a ratchet, a 115 pawl-rod carrying a pawl, a spring to force said pawl-rod toward said cylinder, and a cam secured on said cylinder and adapted to push said pawl-rod and turn said pattern-drum at every revolution of said cylinder, as 120 and for the purpose specified.

11. The combination of the needle-cylinder provided with needles, the loop-wheel, feed-rolls, a table, yarn-guides pivoted on said table and adapted to clamp between their inner 125 ends and said table yarns, and having adjustable followers provided with downwardly-projecting rear ends, beveled as described, a pattern-tape having slots to receive said rear ends, the pattern-drum and the carrier-roll, a ratchet secured on said pattern-drum concentric therewith, a pawl-rod carrying a pawl 130 which engages said ratchet, a spring to force said pawl-rod toward said cylinder, and a cam

secured on said cylinder and adapted to push said pawl-rod and to turn said pattern-drum at every revolution of said cylinder, said cam having two cam-surfaces, and an intermediate 5 rest between said cam-surfaces to allow a new yarn to enter before the old yarn is severed, as and for the purpose specified.

12. The combination of the needle-cylinder provided with needles, the loop-wheel, a table, 10 yarn-guides pivoted thereon and adapted to clamp the yarns between their ends and said table, the pattern-drum actuating said yarn-guides and provided with a ratchet, a pawl-rod carrying a pawl to engage with said 15 ratchet, a cam secured on said needle-cylinder and adapted to push said pawl-rod and turn said pattern-drum at every revolution of said cylinder, and means, substantially as described, for holding said pawl-rod out of 20 the path of said cam, as, and for the purpose specified.

13. The combination of the needle-cylinder provided with needles, the loop-wheel, a table,

yarn-guides pivoted thereon and adapted to clamp the yarns between their ends and said 25 table, the pattern-drum actuating said yarn-guides and provided with a ratchet, a pawl-rod carrying a pawl to engage with said ratchet, a cam secured on said needle-cylinder and adapted to push said pawl-rod and turn 30 said pattern-drum at every revolution of said cylinder, a frame supporting said pawl-rod, said pawl-rod and frame being provided with holes, and a pin adapted to enter said holes to enable said pawl-rod to be drawn out of 35 the path of said cam and there held by inserting said pin in the hole in said frame and in a hole in said pawl-rod, as and for the purpose specified.

In witness whereof I have signed this specification, in the presence of two attesting witnesses, this 3d day of June, A. D. 1889.

MICHAEL J. DINNEEN.
